(57) CLAIM

The ornamental design for a beverage dispenser as shown and described.

DESCRIPTION

FIG. 1 is a front, top and right-side perspective view of a beverage dispenser showing our new design;

FIG. 2 is a front, top and left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The oblique shade lines illustrate a transparent surface.
